[57] **CLAIM**

The ornamental design for a machine for teaching the manner in which a clock indicates time, substantially as shown and described.

DESCRIPTION

FIG. 1 is a front-elevational view of a machine for teaching the manner in which a clock indicates time embodying my new design;
FIG. 2 is a rear-elevational view thereof;
FIG. 3 is a side elevational view of the left side thereof;
FIG. 4 is a top plan view thereof;
FIG. 5 is a bottom plan view thereof.
The side of the machine which is not illustrated is a mirror image of the side of the machine which is illustrated.

FIG. 1.

FIG. 2.

FIG. 3.

FIG. 4.

FIG. 5.
